CABLE TERMINAL

August Aumer, Buffalo, N. Y.

Application May 15, 1933, Serial No. 671,232

Renewed November 23, 1934

3 Claims. (Cl. 173—259)

This invention relates to an improved terminal for a post clamping fixture for a conductor cable such as is used in conjunction with conventional storage batteries.

An object is to produce a terminal having the requisites of simplicity, economy, and commercial appeal.

Other features and advantages will become more readily apparent from the following description and drawings.

In the drawings:

Figure 1 is a top plan view illustrating the preferred embodiment of the invention and showing the manner in which it is utilized.

Figure 2 is a horizontal sectional view thereof.

Figures 3 and 4 are detail perspective views.

Figure 5 is a view similar to Figure 1 showing a different embodiment of the inventive conception.

Figure 6 is a view like Figure 2 but showing the structural details utilized in the arrangement shown in Figure 1.

Figures 7 and 8 are additional perspective views of the details.

Attention is first invited to Figures 1 to 4 inclusive. In Figures 1 and 2 the conventional storage battery is distinguished by the numeral 9 and the customary tapered post is indicated at 10. The post clamp 11 comprises a split annulus 12 which is adapted to embrace the post, said annulus carrying a pair of spaced parallel apertured eyes 13. The conductor or cable is indicated by the numeral 14 and comprises the multiple wound wire core 15 and the external insulation casing 16. In accordance with the present invention, the casing 16 is cut off at one end to expose and allow projection of the bared core. The numeral 17 designates a screw threaded stud or bolt having an adaptor head 18 at one end. This head is of the shape shown in Figure 8 and is sufficiently pointed to permit it to be forced into the wire for secure anchorage. In order to effect a positive connection or coupling between the head 18 and the wire core

15 I have found it expedient and practicable to utilize a tapered bushing 19. The bushing is formed with longitudinal slits 20 which extend through one end to define spring clamping fingers 21. The inner end of the slots terminate short of a portion 22 which may be distinguished as a collar and this collar is internally screw threaded as indicated at 23 and functions as a nut for feeding the bushing on the stud and over the core 15 in sleeve forming relationship as shown in Figure 2. The outer end of the stud

extends through and beyond the eyes 13 where it is adapted to accommodate a clamping and retaining nut 24. The numeral 25 designates an imperforate frusto-conical contraction sleeve which fits over the bushing to serve as a retention and binding element. The numeral 26 merely designates a washer which is interposed between the inner end of the contracting sleeve and the adjacent apertured eye 13.

In assembling the structure the spear-like or pointed head 18 is forced into the wire core 15 in an obvious manner. Then, the bushing 19 is threaded into place to take the position shown in Figure 2. Then the contraction sleeve 25 is slipped up over the bushing and stud and as it is forced outwardly or longitudinally from right to left in Figure 2 it binds the fingers 20 tightly in order to effect a permanent connection between the stud 17 and the wire core 15. The extreme right hand portion of the stud extends through and beyond the eyes 13 to accommodate the nut 24 and the nut serves not only to speed the sleeve 23 into binding position but simultaneously serves to secure the clamp 11 on the battery post 10.

Attention is now invited to Figures 5 and 6 showing a modification of the invention. The battery, post, and clamp are designated by the same reference characters already utilized in Figures 1 and 2. The cable is distinguished by the numeral 26 and comprises a wire core 27 and an insulation covering or casing 28. In this arrangement the terminal is adapted to be built into the cable at the time of manufacture. This result is satisfactorily accomplished by using a different type bushing 29. As shown in Figure 7 this comprises a neck or collar 30 internally screw threaded as indicated at 31 and an integral sleeve 32 of appropriate taper. A substantially T-shaped slot comprising a longitudinal main slot 33 and a short transverse head slot 34 is provided here. The spear head 34 on the screw threaded stud 35 is forced into the wire core and threaded through the collar as shown in the assembly in Figure 6. The bushing 29 is slipped over the core and is tightly clenched in place to join the stud and core together in permanent relationship. The entire sleeve or bushing 29 is here covered with the insulation covering 28. The numeral 36 merely designates a stop nut on the stud located adjacent one of the apertured eyes 13 as shown in Figure 6 so that the take-up action of the nut 24 does not effect the coupling of the stud to the core. As before stated, in this

arrangement, the stud is already built into the cable at the time of manufacture.

It is thought that persons skilled in the art to which the invention relates will be able to obtain 5 a clear understanding of the invention after considering the description in connection with the drawings. Therefore, a more lengthy description is regarded as unnecessary.

10 Minor changes in shape, size, and rearrangement of details coming within the field of invention claimed may be resorted to in actual practice, if desired.

I claim:

15 1. In a structure of the class described, a conductor cable embodying a wire core and an insulation covering therefor, the covering terminating short of one end of the core, a screw threaded stud having a pointed head embedded in said projecting end of the core, a tapered longitudinally slit bushing having a screw threaded collar at one end, said collar being threaded on the stud into abutting relationship with the core, a frusto-conical binding sleeve fitting over said collar and slotted portion of the bushing, together with a split ring post clamp having apertured eyes, the free end portion of the stud extending through and beyond the eyes, and a nut on the extreme outer end of said stud, said nut serving to simultaneously move the eyes toward each other to secure the clamp in place and at the same time to longitudinally adjust said bushing relative to said sleeve to bind the bushing firmly into clamping 30 contact with said core.

2. A cable terminal, comprising a screw threaded stud adapted to be arranged in abutting relationship with the cable, a tapered, longitudinally slit bushing having a screw threaded collar at one end, said collar being threaded on said stud 5 with said bushing embracing said cable, a tapered binding sleeve fitting over the collar and slotted portion of said bushing, together with an apertured support, the free end of said stud extending through and beyond said aperture, and a nut 10 on the free end of said stud, the tightening of said nut serving to clamp said support between said nut and sleeve and at the same time to longitudinally adjust said sleeve relative to said bushing to bind the bushing firmly into clamping 15 contact with said cable.

3. A cable terminal comprising, a screw threaded stud having a pointed head embedded in the end of the cable, a tapered longitudinally slit bushing having a screw threaded collar at one 20 end, said collar being threaded on the stud, a tapered binding sleeve fitting over said collar and slotted portion of the bushing, together with a split ring post clamp having apertured eyes, the free end portion of the stud extending through 25 and beyond the eyes, and a nut on the extreme outer end of said stud, said nut serving to simultaneously move the eyes toward each other to secure the clamp in place and at the same time to longitudinally adjust said bushing relative to 30 said sleeve to bind the bushing firmly into clamping contact with said cable.

AUGUST AUMER.
